UNITED STATES PATENT OFFICE

HENRY LA MOTTE, OF MINNEAPOLIS, MINNESOTA, ASSIGNOR, BY DIRECT AND MESNE ASSIGNMENTS, OF ONE-HALF TO HARRY RONDEAU, OF LITTLE CANADA, MINNESOTA

SEWER CLEANER

Application filed March 30, 1931. Serial No. 526,230.

This invention relates to devices for cleaning and unclogging sewers and other conduits.

In many instances conduits become thoroughly clogged with foreign material and it is difficult to remove or flush out the obstruction. In the case of sewers or other underground conduits employing drain tile or lapped pipe, roots and other plant growths work their way through the joints of the tiles and spread out within the interior of the conduit, growing rapidly and eventually causing a complete obstruction.

It is an object of my invention to provide a simple and highly efficient conduit cleaning device having a working end which may be projected into a conduit from a convenient and accessible point, such as a Y-branch or lateral fitting and which will cut out, scrape, loosen and disintegrate an obstruction.

More specifically it is an object to provide a highly efficient device of the class described which embodies a rotary cutting head adapted to fit the interior of a conduit and carrying an auger or drilling element adapted to disintegrate roots, foreign material and other hard obstructions disposed within the conduit, said head being driven by means of a flexible driving shaft encased in a flexible conduit and coupled with a source of power mounted exteriorly of the conduit.

A further object is to provide in a device of the class described, self-adjustable cutting or scraping blades adapted to conform to the cross sectional shapes of conduits varying considerably in diameter and further adapted to center the head properly for driving.

These and other objects and advantages of the invention will be more fully set forth in the following description made in connection with the accompanying drawings, in which like reference characters refer to similar parts throughout the several views, and in which:

Fig. 1 is a view in vertical section showing my cleaning device applied in a sewer or drain conduit disposed below ground and extending from the basement of a building;

Fig. 2 shows the rotary cutting head of

my device in larger scale applied in a portion of a conduit;

Fig. 3 is a cross section taken on the line 3—3 of Fig. 2;

Fig. 4 is a cross section taken through a conduit wherein my device is applied, the rotary cutting head being shown in front end elevation;

Fig. 5 is a top plan, some portions being broken away showing the truck mounting for the driving motor of my device and the driving connections;

Fig. 6 is a fragmentary sectional view taken longitudinally through a suitable form of flexible driving shaft and casing therefor, and

Fig. 7 is a detail view illustrating the shank or driving end of the flexible shaft shown in Fig. 6.

In the drawings an embodiment of my invention is shown operatively applied to an underground sewer conduit C which comprises the conventional lapped tiles, disposed below the floor F of the basement of a building. The vertical portion of the conduit C is provided with a Y-branch or fitting B which has a removable plug not shown in the drawings.

My device utilizes a self-adjustable rotary cutting head comprising a hub 8 having a longitudinal slot in one end thereof for receiving a shank or tongue 9 which is coupled with one end of a flexible driving shaft.

Hub 8 carries a series of pivoted cutting blades 10, said blades being formed in the manner of fly-ball levers pivoted adjacent their inner ends to supporting ears 8a carried by the hub and arranged circumferentially thereof. Although any suitable number of these blades 10 may be provided, in the drawings the hub 8 is shown as carrying three blades. The inner ends of the pivoted cutting blades may be interconnected in the manner shown in Figs. 3 and 2 by means of coil springs 11 to normally force the outer and longer cutting portions 10a of the blades outwardly. If desired these springs may be dispensed with as centrifugal force effected by the rotation of the head is sufficient to urge the cutting portions 10a outwardly. Hub 8

at its forward end carries an axially projecting auger 12 which may be, if desired, integrally formed therewith and as shown the tip of said auger terminates adjacent the plane defined by the forward ends of the elongated cutting portions 10a when said cutting portions are in the average spread position.

My cutting head is driven by a suitable source of rotary power disposed exteriorly of the pipe or conduit to be cleaned and in the embodiment of the invention illustrated I provide a motor M of adequate power rigidly mounted on the platform of a wheeled truck T which truck, if desired, may be supported on a portable track P comprising spaced rails secured together by cross bars at their ends. As shown, the armature shaft of the motor is disposed transversely of the truck and is coupled with a worm 13 journaled in a suitable frame 14, which worm meshes with a worm gear 15 fixed to a shaft 16 which is mounted in suitable bearings and extends longitudinally of truck T. Shaft 16 is connected by a coupling 17 with the shank 18a of an elongated flexible driving shaft 18 which may be of any suitable construction and which as illustrated comprises a multiplicity of flexibly connected links. Flexible driving shaft 16 is encased by a flexible conduit 19 and the outer end of said conduit may be clamped by a bracket 20 fixed to the forward end of the truck T. The forward end of the flexible driving shaft, as clearly shown in Fig. 2, is flexibly connected with the hub 8 of the cutting head by means of the twisted link or tongue 9.

In operation when it is desired to remove and disintegrate an obstruction in a sewer pipe or other conduit, the Y-branch B is opened or if no Y-branch is provided, a suitable opening is made in one of the sections or portions of the conduit and the cutting head of my device is inserted through the opening and thrust through the conduit in the direction of the obstruction. The power may be turned on after the head is within the conduit and the rotation of the head, due to its shape and the auger or screw mounted thereon, will tend to move the device forwardly toward the obstruction. Centrifugal force of the rotating head causes the cutting arms 10a to be thrown outwardly uniformly against the inner periphery of the conduit and by reference to Fig. 4 it will be seen that the sharpened edges of the cutting blades closely scrape the conduit, cutting and removing foreign matter, accumulations and other obstructions.

One of the greatest difficulties with sewers and drains of the lapped tile type is the growth and presence of roots within the conduit. With my device the cutting blades quickly cut and remove all roots and plant growths. Substantially at the same time

that the circumferentially arranged cutting blades scrape the inner periphery of the conduit, the point of auger 12 engages the central portion of the obstruction, boring through and disintegrating the same and when the obstruction is engaged the auger will of course force the cutting head through the same.

The circumferentially arranged cutting arms 10 operate in the manner of fly ball levers on a governor and if desired the springs 11 may be utilized to urge the cutting ends of said arms outwardly with greater force. It will be noted that the disposition and construction of the arms perfectly centers the cutting head within the conduit making the head self-adjustable for conduits varying considerably in internal diameter. The outward swinging of the cutting blades 10a is of course limited by the engagement of the shorter portions of the arms or levers with the hub 8.

The flexible driving shaft is conveniently driven by the source of power mounted exteriorly of the conduit and while various means may be provided for mounting the source of power, I prefer the use of a wheeled truck T which can be moved toward or from the conduit easily if desired. An additional advantage is obtained if the wheels of the truck are mounted upon spaced rails of a track, thus eliminating the lateral displacement of the motor supporting member due to the driving of the flexible element 18.

From the foregoing description it will be seen that I have provided a comparatively simple but highly efficient cleaning device for sewers and conduits which is adapted to be easily applied to the interior of a conduit and which is effective to very quickly loosen, cut and disintegrate an obstruction located therein.

It will, of course, be understood that various changes may be made in the form, details, proportions and arrangement of the parts without departing from the scope of my invention, which, generally stated, consists in a device capable of carrying out the objects above set forth and in the novel parts and combinations of parts disclosed and defined in the appended claims.

What is claimed is:—

1. A rotary cutting head for cleaning sewers and other conduits comprising, a central hub, an axially aligned drilling element at the forward end thereof and a series of circumferentially arranged arms pivoted to said hub to permit outward movement of their forward portions whereby when said head is rotated, centrifugal force will cause outward movement of the forward portions of said arms.

2. The structure defined in claim 1, the said arms having sharpened advancing edges.

3. The structure defined in claim 1, said

arms being arcuately curved adjacent their forward ends and having pointed tips, the advancing edges of the arms being sharpened.

8. 4. A rotary cutting head for cleaning sewers and other conduits having a central hub, a plurality of circumferentially arranged arms pivoted to said hub to permit outward movement of their forward portions, 10 and means for driving said head in one direction, said arms being arcuately curved adjacent their forward ends with their concave surfaces disposed inwardly, the advancing edges of said arms being sharpened to form 15 knives.

5. A rotary cutting head for cleaning sewers and other conduits comprising, a hub, an axially extending boring element projecting forwardly from the hub, a plurality of 20 cutting arms pivoted to said hub to permit outward movement of their forward portions said forward portions projecting ahead of said hub and the rear portions of said arms projecting behind said boring element and 25 coiled springs located behind said boring element and connected with the rear portions of said arms to exert resilient tension on said arms to carry the forwardly projecting portions thereof radially outwardly.

30 6. A rotary cutting head for cleaning sewers and other conduits, comprising a central hub, an axial boring element applied to said hub, projecting forwardly therefrom and a plurality of circumferentially arranged arms 35 pivoted at their medial portions to said hub so as to normally be disposed substantially parallel to the axis of said hub, said arms having forward portions of arcuate-shape with their concave sides turned inwardly, 40 the forward portions of said arms having sharpened advancing edges forming knives and said arms being twisted slightly at their forward portions, so that the sharpened

edges of the arms project outwardly a slightly greater distance than the other edges thereof.

7. A rotary cutting head for cleaning sewers and other conduits comprising, a central hub, an axially aligned drilling element at the forward end thereof, a series of circumferentially arranged arms pivoted to said hub to permit outward movement of their forward portions, and means for moving the forward portions of said arms outwardly. 70

8. A rotary cutting head for cleaning sewers and other conduits, having a central hub, an axially aligned drilling element at the forward end thereof, a plurality of circumferentially arranged arms pivoted to said hub to permit outward movement of their forward portions, means for causing outward movement of said forward portions, and means for driving said head in one direction, said arms being arcuately curved adjacent their forward ends with their concave surfaces disposed inwardly, the advancing edges of said arms being sharpened. 80

9. A rotary cutting head for cleaning sewers and other conduits comprising a central hub, an axially aligned drilling element at the forward end thereof and a series of circumferentially arranged arms normally disposed substantially parallel to the axis of said hub and pivotally connected thereto near their rearward ends to permit movement of the forward ends of said arms to and from the axis of said hub, springs for urging the forward ends of said blades outwardly, said arms having sharpened advancing edges to form cutting blades, the cutting edges of said blades being respectively located but slightly further from said hub than the opposite edges thereof. 90

In testimony whereof I affix my signature.

HENRY LA MOTTE.
